UNITED STATES PATENT OFFICE.

GEORGE JAMES MANSON, OF TORONTO, ONTARIO, CANADA.

PULP GRINDER.

Application filed March 15, 1919, Serial No. 282,781. Renewed August 14, 1923.

To all whom it may concern:

Be it known that I, GEORGE JAMES MANSON, a subject of the King of Great Britain, and resident of Toronto, in the Province of Ontario, Dominion of Canada, have invented certain new and useful Improvements in Pulp Grinders, of which the following is a specification.

This invention relates to improvements in pulp grinders, and the objects of the invention are to provide a simple and effective form of grinding in which relatively long fibres may be produced and in which the entire grinding surface will be availed of in the grinding operation.

The grinder is especially designed to be used in the production of fibres from saw-mill waste, such as slabs, edgings, saw dust, shavings and the like which has previously been chipped to suitable size.

The invention consists essentially of the grinder construction all as hereafter arranged and shown in detail in the accompanying specification and drawings.

In the drawings:

Figure 1 shows an elevation partly in section of the grinder.

Figure 2 is a detail in plan showing one end of the grinder.

Figure 3 is an end view of the surface of the grinding stone.

Figure 4 is a section through the grinding surface on the line 4-4 of Figure 3.

Figure 5 is a section of the grinding surface on the line 5-5 of Figure 3.

Figure 6 is a section through the grinding surface on the line 6-6 of Figure 3.

Figure 7 is a section through the grinding surface on the line 7-7 of Figure 3.

Referring to the drawings, A represents a suitable base having standards 10, 11 and 12 which support the shaft B adapted to be turned by a convenient source of power conveniently applied to the shaft through the pulley 13.

Means are provided for adjusting the shaft in an axial direction. The well known means which I show to accomplish this purpose comprise a hand wheel 14 adapted to turn a pinion 15 which meshes with gears 16 and 17 connected to screw shafts 18 and 19 which extends through a travelling element 20 which has a collar 21 fitting between the collars 22 and 23 on the shaft B. Ball bearings 24 are shown between the collar 21 and the collars 22 and 23. Any other con-

venient and well known means for adjusting the shaft in a lengthwise direction may be employed.

C represents the rotary grinding element which is conical in form, the outer surface being substantially at an angle of 30° to the axis. This element is secured to and rotates with the shaft B and is adapted to co-operate with the fixed element D of the grinding pair which is secured to the fixed casing E.

Material is adapted to be fed between the grinding element from a feeding chamber 30 at the small end of said members and the ground pulp is adapted to be withdrawn from the larger peripheries of the grinding pair from the outlet box 31. The passage of material between the grinding stones may be facilitated by a screw blade 32.

The grinding elements may each be manufactured of stone, I prefer to manufacture them from a mixture of cement and sharp sand, about 50% of each mixed with about 10% of saw dust to form voids. In some cases one of the elements may be made of cast metal such as cast iron.

The rotary grinding element C is provided on its surface with a plurality of feeding grooves 33 which extend in a spiral manner around the periphery and are gradually decreased in depth from their commencement at the small end of the cone to their end near the large end of the cone, this gradual decrease being indicated in the sectional views Figures 4 to 7. The groove at its commencement is formed substantially rectangular with the side walls opening downwardly slightly the angle of the side walls are gradually increased and they are converged at the bottom until the grooves run out. This is the fact of gradually forming the stock out between the grinding surfaces as it is fed by centrifugal force.

To assist in the distribution of the stock, a plurality of subsidiary grooves 34, 35 and 36 are provided for each principal groove 33, these subsidiary grooves extending parallel to each other at an angle to the main groove 33 and being designed to distribute the stock over the grinding surface. The subsidiary grooves also gradually decrease in operating from their point of abjunction with the main grooves 33 to their extremities.

In operating raw material such as saw mill waste, it is first chipped and then mixed with water until the mixture contains about

10% of chips and 90% of water. This is fed by gravity between the grinding surfaces at the small end thereof. The space between the grinding element is so set that there will 5 also be a space for a plurality of fibres between the surfaces in this way relatively long fibres are produced due to the fact that the comminution is produced rather by the fibres rubbing one against the other than 10 by being rubbed directly between the grinding surfaces.

The stock is fed continuously in order that there may be at all time a continuous film of stock between the surfaces.

15 As many changes could be made in the above construction, and many apparently widely different embodiments of my invention within the scope of the claims, constructed without departing from the spirit

or scope thereof, it is intended that all matter contained in the above specification and accompanying drawings shall be interpreted as illustrative and not in a limiting sense.

What I claim as my invention is:

1. In a pulp grinder, a grinding element 25 formed of cement, sharp sand and combustible material adapted to produce voids therein.

2. In a pulp grinder, a grinding element 30 formed of the following ingredients in the proportions stated; cement and sand equal parts and 10 per cent of sawdust.

In witness whereof I have hereunto set my hand in the presence of a witness.

GEORGE JAMES MANSON.

Witness:

RUSSEL S. SMART.
